(57) **CLAIM**

The ornamental design of a shopping cart handle, as shown and described.

DESCRIPTION

FIG. 1 is a perspective view of the shopping cart handle of the present invention.

FIG. 2 is a left side view of the shopping cart handle of FIG. 1, the right side view being a substantial mirror image thereof.

FIG. 3 is a top view of the shopping cart handle of FIG. 1. FIG. 4 is a bottom view of the shopping cart handle of FIG. 1.

FIG. 5 is a front view of the shopping cart handle of FIG. 1; and,

FIG. 6 is a back view of the shopping cart handle of FIG. 1. The broken lines shown in FIG. 1 are for illustrative purposes only and form no part of the claimed design.
